REMOTE BURNER LIGHTER

Bo Karl Georg Ehnborn, Stockholm, Sweden

Application August 23, 1941, Serial No. 408,027
In Germany March 7, 1941

12 Claims. (Cl. 62—1)

This invention relates to gas burners and more particularly to igniting a remotely located gas burner.

It is an object of the invention to provide for remote lighting of a burner such as a gas burner positioned at the rear of a heat operated refrigerator which it is desired to light from the front of the refrigerator.

The nature of the invention and the advantages thereof are set forth in the following description in connection with the accompanying drawings forming a part of this specification and of which:

Figure 1 is a vertical section of the bottom portion of a domestic refrigerator having installed therein a gas burner embodying the invention:

Figure 2 is a view showing partly in section the burner of Figure 1; and,

Figure 3 is a sectional view on the line 3—3 of Figure 2.

Referring particularly to Figure 1 of the drawings, a refrigerator cabinet, indicated generally at 2, has mounted at its rear a continuous absorption refrigeration unit, and the figure shows at the right the bottom portion of the generator 4. This generator has a vertical flue 6 beneath which is rigidly mounted on a bracket bar 50 a gas burner, generally indicated at 10 and the details of construction of which are shown in Figures 2 and 3. The gas burner is generally like that described in Patent No. 2,069,062, granted January 26, 1937. Referring particularly to Figure 2, the burner 10 is provided with a gas supply passage 11 suitably threaded at its upper end 12 for connection to a gas supply pipe. In the upper portion of passage 11 there is inserted what may be generally referred to as a safety cut-off valve assembly 13 comprising a valve body 14, a valve member 15, a valve stem 16, a snap action thermostatic diaphragm 17, a diaphragm housing 18, and a heat conductor 19. The valve member 15 is connected by the valve stem to the center of the thermostatic diaphragm 17 the periphery of which is secured in the housing 18. The heat conductor 19 has one end located in a position to be heated by the burner flame and the other end secured to the housing 18 so that when the burner is lighted, heat is conducted to the thermostatic diaphragm 17.

At the lower part of the burner housing, passage 11 is connected through an opening 21 to a second passage 20. The effective area of opening 21 is adjusted by turning an adjustment screw which is threaded in the lower end of passage 11 and the upper end of which is shown at 50

22. A suitable cap screw 23 is provided for sealing the lower end of passage 11 and is removed for permitting access to the adjustment screw 22. The setting of screw 22 determines the maximum flow of gas to the burner and therefore the maximum size of the burner flame. At the left, passage 20 opens into the bottom of the burner proper which is indicated at 30 and the details of which are shown in the patent referred to above. This burner mixes air with the gas, and the gas and air mixture flows from the top openings 40, maintaining a flame which heats generator 4. The flame also heats conductor 19 so that heat is transmitted to housing 18 and to the thermostatic diaphragm 17, and when the thermostatic diaphragm is thus maintained heated, it holds valve member 15 open. If for any reason the burner flame becomes extinguished, the conductor member 19 and the thermostatic diaphragm 17 cool down until the diaphragm flexes to the position shown in Figure 2 snapping the valve member 15 to the closed position and cutting off flow of gas to the burner. When it is desirable to light the burner, the thermostatic diaphragm 17 is heated until it opens the gas valve. As a result of this, gas is supplied to the burner, and the burner is then ignited by the same flame that is used for heating the thermostatic diaphragm.

30 Initially, the thermostatic diaphragm is heated, and the burner is ignited by means of an igniting burner positioned beneath housing 18 and indicated at 60. Burner 60 is in the form of a horizontally positioned, cylindrical plug 61 rigidly mounted at its right end and having its left end cut away as shown in Figures 2 and 3. Burner 60 is provided with an upwardly directed jet 62 and a horizontal jet 64 which are connected through horizontal passageways in plug 61 to a chamber 66. As shown in Figure 3, chamber 66 is connected by a passage 68 to an auxiliary gas supply passage 70, and passage 70 is provided with a ball-and-spring valve having a coil spring 72 which normally holds a valve ball 74 against a valve seat. Referring to Figure 2, the end of passage 70 is connected through an upward passage 76 to the gas inlet of passage 11. Thus, when valve ball 74 is unseated, gas is supplied to jets 62 and 64 independent of the supplying of gas to the main burner through passage 11.

55 Valve ball 74 may be unseated by sliding a valve operating pin 78 (Figure 3) toward its depressed position. Pin 78 extends through a cap 80, there being a sliding fit around the pin so that gas does not escape, and spring 72 is held in

place by a cap 82. Pin 78 is slid inwardly by means of an operating arm 88 riveted to a tube 84. The inner end of tube 84 is slideably supported by a collar bracket 86 welded to the burner and having a collar portion snugly receiving the end of the tube. Referring to Figure 1, tube 84 extends from the burner to the front of the refrigerator cabinet and has its outer end slideably carried by a bracket 90 mounted upon the lower wall of the refrigerator cabinet. Welded to the outer end of tube 84 is an operating handle 92 which carries at its top a guide pin 94 the right-hand end of which is slideably received in an opening in bracket 90. A compression spring 96 is coiled about tube 84 between bracket 90 and operating handle 92, and at the right of bracket 90 and welded to tube 84 is a collar 98. Spring 96 tends to slide the tube to the left, and collar 98 limits the movement so that the tube is normally held in the position shown. However, handle 92 is so spaced from bracket 90 that the two may be grasped, and by squeezing the handle and the bracket, the tube is slid to the right against the action of spring 96 with the result that pin 78 displaces valve ball 74 (Figure 3) from its seat and gas is supplied to jets 62 and 64.

Jet 64 is directed into the open end of tube 84, and when the tube is moved to the right, its end is adjacent the jet. Thus, gas from the jet passes through tube 84 where it mixes with air, and the mixture emanates through the front end of the tube. This mixture is ignited by holding a flame at the front end of the tube adjacent handle 92, and the flame will immediately travel back through the tube, and at the rear of the tube the gas from jets 62 and 64 is ignited. Due to the fact that flames are maintained at the jets, no more gas passes through tube 84, but the flames extend upwardly (Figure 2) so as to heat the thermostatic diaphragm 17. When the thermostatic diaphragm is sufficiently heated, it snaps to the right and opens valve 15 so as to supply gas to the main burner. As this gas passes from openings 40, it is ignited by the flame from jets 62 and 64. Handle 92 (Figure 1) is then released so that valve ball 74 is re-seated, shutting off the supply of gas to the igniting burner.

I claim:

1. In a heat operated refrigerator having a cabinet to which access may be had at the front and having a generator which is heated to operate the refrigerator, the combination with said generator of a main burner, and igniting means to ignite said burner comprising an igniting burner mounted upon said main burner, valve means which is operated to supply fuel to said igniting burner independent of the supplying of fuel to said main burner, a pair of brackets one of which has a tube receiving portion adjacent said igniting burner and the other of which has a tube receiving portion adjacent the front of said cabinet, a tube slideably mounted in said tube receiving portions and adapted to be slid inwardly toward said igniting burner, said tube having a handle means rigidly mounted at its forward end, and an operating arm mounted adjacent said burner and mechanically related to said valve means so that said valve means is operated when said tube is slid inwardly toward said igniting burner.

2. In a heat operated refrigerator having a remotely located burner, an igniting mechanism comprising a plurality of gas jets, a tube having an opening at each end with one opening

positioned to receive gas from one of said jets and with the other opening conveniently positioned with respect to the side wall of the refrigerator, means movably mounting said tube, valve means to control the supply of gas to said gas jets, mechanism carried by said tube and operable to open said valve means upon movement of the tube in one direction, and means to close said valve upon movement of the tube in the opposite direction and to normally maintain said valve in closed position, said mechanism being so constructed and arranged that upon movement of said tube in said one direction said gas valve is opened and gas flows from said one jet through said tube to the opposite end thereof, that is conveniently positioned with respect to the side walls of the refrigerator whereby this gas may be ignited to carry a flame back through said tube to another of said gas jets.

3. In a heat operated refrigerator having a remotely located burner, an igniting mechanism comprising a plurality of gas jets, one of said jets being directed toward the burner, a tube having an opening at each end with one opening positioned to receive gas from another of said jets and with the opening at its opposite end conveniently positioned with respect to the side walls of the refrigerator, means movably mounting said tube, valve means to control the supplying of gas to said gas jets, mechanism carried by said tube and operable to open said valve means upon movement of the tube in one direction, and means to close said valve upon movement of the tube in the opposite direction and to normally maintain said valve in closed position, said mechanism being so constructed and arranged that upon movement of said tube in one direction said gas valve is opened and gas flows from said one jet through said tube to the opposite end thereof that is conveniently located with respect to the side walls of the refrigerator, whereby said gas may be ignited to carry a flame back through said tube to said other gas jet directed toward said burner.

4. In a heat operated refrigerator having a remotely located burner, an igniting mechanism comprising a plurality of gas jets, a tube having an opening at each end with one opening positioned to receive gas from one of the said jets and with the other opening conveniently positioned with respect to the side walls of the refrigerator, said tube being mounted for longitudinal sliding movement on a pair of downwardly extending brackets, a hand grasp rigidly mounted on said tube adjacent one of the brackets for sliding the tube longitudinally, valve means to control the supply of gas to said gas jets, mechanism carried by said tube and operable to open said valve means upon sliding movement of the tube in one direction, and means to close said valve upon movement of the tube in the opposite direction and to normally maintain said valve in closed position, said mechanism being so constructed and arranged that upon movement of said tube in said one direction said gas valve is opened and gas flows from said one jet through said tube to the opposite end thereof that is conveniently positioned with respect to the side walls of the refrigerator, whereby this gas may be ignited to carry a flame back through said tube to another of said gas jets.

5. In combination with a main burner having an inlet and an outlet, an igniting burner comprising a plurality of gas jets operable to ignite said main burner, one of said jets being di-

rected toward the main burner and a second jet being directed at an angle to the first jet, valve means to control the supply of gas to said main burner, valve means to control the supply of gas to said igniting burner, an open ended flash-over tube movably mounted relative to said igniting burner and having one end positioned adjacent said igniting burner and in alignment with the second mentioned jet thereof, the other end of said flash-over tube being positioned at a point remote from said igniting burner, and structure operatively connected to said flash-over tube and operable by said tube upon movement thereof toward said igniting burner to open said igniting burner gas valve, whereby gas issuing from one of said jets will pass directly into said flash-over tube and gas issuing from another of said jets will be directed toward said main burner outlet.

6. In combination with a main burner having an inlet and an outlet, an igniting burner comprising a plurality of gas jets disposed in an angular relation to each other, a main gas valve for said main burner, a thermostat to control said main valve, an auxiliary valve to control the supply of gas to said igniting burner, an open ended flash-over tube mounted for longitudinal movement relative to said igniting burner, one of the jets of said igniting burner being directed toward the main burner and thermostat and another jet being aligned with the flash-over tube, structure operatively connected to said flash-over tube and operable by said tube upon movement thereof toward said igniting burner to open said auxiliary valve, and means to close said auxiliary valve upon movement of said flash-over tube away from said igniting burner, whereby upon opening of said auxiliary valve gas flowing from one of said jets will be directed into said flash-over tube and gas flowing from another of said jets will be directed toward said thermostat and said main burner outlet.

7. In combination with a main burner having an inlet and an outlet, an igniting burner comprising a plurality of gas jets operable to ignite said main burner, one of said jets being directed toward the main burner and a second jet being directed at an angle to the first jet, valve means to control the supply of gas to said main burner, valve means to control the supply of gas to said igniting burner, an open ended flash-over tube mounted for longitudinal movement relative to said igniting burner and having one end positioned adjacent said igniting burner and in alignment with the second jet of the latter, the opposite end of the flash-over tube being positioned at a point remote from said igniting burner, spring means to oppose the longitudinal movement of said flash-over tube toward said igniting burner and to oppose the opening of said valve means, and structure operatively connected to said flash-over tube and operable by said tube upon movement thereof toward said igniting burner to open said igniting burner gas valve in opposition to said spring means, whereby gas issuing from one of said jets will pass directly into said flash-over tube and gas from another of said jets will pass toward said main burner outlet.

8. In combination with a main burner having an inlet and an outlet, a thermostatically operated cut-off valve for shutting off the supply of gas to said main burner when the temperature falls below a predetermined value indicating

that the burner flame has been extinguished, an igniting burner comprising a plurality of gas jets operable to ignite said main burner, one of said jets being directed toward the main burner and valve thermostat and a second jet being directed at an angle to the first jet, valve means to control the supply of gas to said igniting burner, an open ended flash-over tube movably mounted relatively to said igniting burner and having one end positioned adjacent said igniting burner and in alignment with the second jet thereof, the opposite end of said flash-over tube being positioned at a point remote from said igniting burner, and structure operatively connected to said flash-over tube and operable by said tube upon movement thereof toward said igniting burner to open said igniting burner gas valve whereby gas issuing from one of said jets will pass directly into said flash-over tube and gas issuing from another of said jets will pass toward said main burner and thermostatically operated cut-off valve, the flame of said igniting burner being utilized initially to heat the thermostatic element of said thermostatically operated valve to thereby reopen the valve and supply gas to said main burner.

9. In combination with a main burner positioned in a relatively inaccessible location, an igniting burner for igniting said main burner and arranged in juxtaposition therewith, a valve arranged adjacent said igniting burner for controlling the supply of gaseous fuel thereto, and a flash tube movably mounted and having one end adjacent said igniting burner and the other end at a relatively accessible point remote from said igniting burner, said flash tube being so connected to said valve that said valve is opened by movement of said flash tube.

10. In combination with a main burner positioned in a relatively inaccessible location, an igniting burner for igniting said main burner and arranged in juxtaposition therewith, a valve arranged adjacent said igniting burner for controlling the supply of gaseous fuel thereto, and a flash tube mounted for endwise movement toward and away from said igniting burner and having one end adjacent said igniting burner and the other end at a relatively accessible point remote from said igniting burner, said flash tube being so connected to said valve that said valve is opened by movement of said flash tube toward said igniting burner.

11. In combination with a gas burner positioned in a relatively inaccessible location, a body member housing both an igniting burner and its control valve and positioned adjacent said gas burner, a flash tube movably mounted with one end adjacent said body member and the other end at a relatively accessible point remote from said body member, and a connection whereby said valve is operated by movement of said flash tube.

12. In combination with a gas burner positioned in a relatively inaccessible location, a body member positioned adjacent said gas burner and housing a no-flame safety cut-out valve for said gas burner, an igniting burner, a control valve for the latter, a flash tube movably mounted with one end adjacent said body member and the other end at a relatively accessible point, and a connection whereby said control valve is operated by movement of said tube.
